APPARATUS FOR FLOWING OIL WELLS

Homer R. Toney, Vivian, La., assignor of one-half to John R. Beddingfield, Shreveport, La.

Application May 23, 1938, Serial No. 209,617
Renewed May 31, 1940

2 Claims. (Cl. 103—233)

This invention relates to an apparatus of flowing wells particularly oil wells which do not have sufficient internal gas pressure to discharge the contents of the well.

5 The object of the present invention is to enable oil wells to be flowed by means of a gas or pneumatic lift and to utilize for this purpose the conventional well casing and oil flow tube.

Another object of the invention is to construct 10 such a lift for wells having a plurality of longitudinally spaced valves placed between sections of an internal pipe line and to provide a positive means for operating these valves. The automatic valves which have been previously proposed for accomplishing this purpose have not 15 been found practical in use and well operators are never sure that the automatic valves have properly functioned.

A still further object of the present invention 20 is to provide a novel gas lift valve per se which may be positively opened and closed by the introduction of an operator within the pipe line.

In the drawing,

25 Fig. 1 is a diagrammatic sectional view of a well showing a typical installation of the present invention;

Fig. 2 is an enlarged detail view, partly in section of one of the flow valves in closed position;

30 Fig. 3 is a vertical section of the flow valve in opened position and illustrating the valve actuation means;

Fig. 4 is a cross-section view of the flow valve, 35 taken on line 4—4 of Fig. 2 when the valve is about half closed;

Fig. 5 is also a cross-section view of the flow valve taken on line 4—4 of Fig. 2 when the valve is closed;

Fig. 6 is a vertical section view of the valve 40 per se taken on line 6—6 of Fig. 5.

Specifically in the drawing numeral 10 indicates a conventional well casing extending downwardly from the surface into an oil bearing strata. The usual pipe line 11 is positioned within the 45 casing 10 and is sealed off the casing near the bottom thereof by packer 12. A smaller diameter flow pipe 15 is placed within pipe line 11, and extends therefrom above the surface where it is led to a suitable tank or reservoir 16. A 50 casing head seal 17 is secured to the upper end of pipe line 11 through which flow line 15 passes. The sealing head 17 is provided with a fluid supply pipe 18 for conveying gas or compressed air from gas supply pipe 19 or compressor 20 to pipe 55 line 11.

A series of low valves 25 are placed in the flow pipe 15 at suitable intervals so as to be located at different elevations in the pipe from adjacent the bottom of the well to near the surface level of the oil therein. These flow valves differ from 5 the prior art by reason of the fact that they are positively opened and closed and do not depend for their operation on springs, balls or other automatic means subservient to gas or liquid pressures in the flow pipe and casing.

10 As before stated, one of the prime objects of the present invention is to provide the oil flow pipe with a series of positively opened and closed valves or stop cocks for the purpose of progressively elevating and discharging oil from the 15 well and to enable the operator to walk the lift gas down the well by serially opening and closing the stop cocks as the fluid pressure admitted into the oil pipe lowers the level of liquid therein. With the instant construction of the valve and 20 valve actuator there is no guess work involved as to whether or not a valve has opened or closed, for each actuation is definite and not subject to an involved and delicate automatic structure.

25 Referring to the detail drawing, Figs. 2 to 6, inclusive, it will be seen that each valve or stop cock is made a part of the pipe coupling or joints 25, inserted into the flow pipe 12 at suitable intervals by screw threaded collars 26. The valve coupling 25 is preferably a machined cylinder 30 30 having end threads 27 and a central passage or bore 31 therethrough, the ends of the bore being flared outwardly as denoted by numeral 32. A valve or stop cock assembly 35 is positioned in a longitudinal stepped slot 36 cut in the wall of the 35 cylinder 30, and as seen in Figs. 2 and 3, the slot extends into the side of passage 31.

Essentially, the assembly 35 consists of a machined block having offset arms 37 with screw opening 38 for the reception of screws which 40 firmly retain the assembly in the slot 36. The inner portion of the valve assembly 39 is shorter than the outside portion and fits within the inner portion of the slot 36, as shown, the extreme inner section 40 thereof being curved to 45 conform with the circumference of the bore 31.

The valve or cock per se may take the form of a tapered cylindrical body or plug 45, fitted within a corresponding transverse machined bore 46. A fluid passage or conduit 47 is provided from 50 the exterior to the interior of the assembly and is controlled by bore 48 passing through the plug 45. The plug 45 is rotated or oscillated into open or closed position by means of a curved arm 50 pinned or otherwise fastened on a squared ex- 55

tension 51 of the plug extending through a corresponding opening in the central portion 52 of the arm.

5 A flared groove 53 extends from the bore 31 around the base of the valve arm 50 so that in either position the outer end of the arm terminates just with the bore diameter. In Fig. 4 the solid line position of the arm indicates that it is fully closed, while the dotted lines indicate 10 the arm in intermediate positions, as also does Fig. 5.

15 The valve or stop cock is positively opened or closed by means of a slightly tapered cylindrical operator or weight 55. This weight is made with a straight lower end 56 of slightly less diameter than the bore 31, and the operator is moved into engagement with the valve arm 50 by being suspended from wire 57 which passes through passage 58 and is knotted at the bottom or otherwise 20 secured to the weight. As the weight 55 is lowered from the upper end of the tube 15, it will strike the arm 50 of the uppermost of the series of closed valves 25 and will rotate the same to open position, as seen in Fig. 5. The weight 25 being slightly smaller in diameter than the cylinder bore may readily pass therethrough, but it must contact the outer end of valve arm 50, which projects slightly into the bore.

When it is desired to close a previously opened valve, the weight or operator 55 is reversed on the wire 57 by inverting the weight and tying it at the bottom by passing the wire out of transverse opening 59. This reversal of the weight places the straight surface 56 at the top and as the operator is slightly tapered, it will pass through the bore 31 to a point below the opened valve. However, when the reversed weight is again hoisted the flat top edge will strike the valve arm 50 and close the valve. This 40 action in either direction is further insured by flaring the end of the bore at 32 to direct the operator and by having the wire passage 58 of a size that will cause the weight to be slightly off its true vertical axis and rub against the bore.

45 In operation, a string of one and one-quarter inch oil flow pipes 15, having a series of lift valves 25 coupled therein at suitable intervals, are lowered into the well inside of the usual pipe line 11. Flow pipe 15 passes out of the pipe line 11 through head seal 17 and is joined to a discharge branch leading to tank 16. Fluid pressure to operate the oil lift is supplied to outer pipe line 11 from a source of gas pressure through line 19 or a source of compressed gas 50 or air from compressor 20.

55 To apply pressure to the hydrostatic head of oil which has risen in flow pipe 15, gas pressure or compressed air is introduced into pipe line 11. The union 12 is then broken and the weight 55 on its attached wire 57 is lowered until the flat end 56 strikes the arm 50 of the uppermost series

of valves 25 to open the same, after which the union is closed and the fluid pressure in pipe line 11 then rushes through valve passage 47 and overcomes the hydrostatic head on the oil in the pipe 11 above the stop cock to elevate and discharge the oil into the storage tank. After the oil above the valve has been lifted, the weight is again inserted in reverse position to a point just below the valve and raised to positively close the same. The operation, as before 10 described, is then again instituted to open the second valve and after discharge of the oil, the operation is repeated until the lowermost series of valves has been opened and closed and the well completely emptied. After the well has had 15 sufficient time to fill again, the same steps are taken.

Having thus described my invention, what I claim as new and desire to secure by Letters Patent of the United States is:

1. In a well flowing apparatus, a flow pipe, a pipe line formed of a plurality of sections, couplings connecting adjacent sections, the pipe line being positioned interiorly of the said flow pipe within a well casing, said pipe line having 25 longitudinally spaced apart, manually operable valves positioned in the couplings for establishing communication between the interior and exterior of said pipe line, means for introducing a gaseous pressure medium into the space between said flow pipe and said valved pipe line, said individual valves each comprising rotary valve bodies having bores therethrough and outwardly extending operating arms secured to one end of said bodies, means cooperating with said operating arms for positively opening and closing said valves, the said valve bodies being mounted in a plate having radial passages therethrough registering with the bores in the valve bodies, the said plates being mounted as units in openings formed in the couplings joining the individual line sections.

2. In an oil well flowing apparatus and in combination with the conventional oil well casing and flow tube, a pipe line within said flow tube, a seal between the upper portions of the tube and pipe, a conduit leading to the space between said tube and pipe for conveying gaseous pressure thereto, said pipe line having a plurality of longitudinally spaced rotary valves 50 therein for establishing communication with the interior of said pipe line, valve operating arms attached to said valves and extending into the interior of said pipe, a valve actuator for oscillating said operating arms comprising an elongated reversible tapered weight secured to a cable and adapted to be manually raised and lowered in said pipe line, said weight oscillating said arms only when struck by the larger end of said tapered weight.

HOMER R. TONEY.
